UNITED STATES PATENT OFFICE

2,669,442

ANNEALING APPARATUS

John E. Erhardt, Jr., Baltimore, Md., assignor to
 Crown Cork & Seal Company, Inc., Baltimore,
 Md., a corporation of New York

Application August 24, 1948, Serial No. 45,847

21 Claims. (Cl. 263—3)

1

The present invention relates to an annealing apparatus, of the type in which continuous strip metal is annealed, during its continuous movement through the apparatus, as distinguished from batch annealing furnaces, in which stacks or rolls of sheets or plates are annealed.

More particularly, the invention relates to an apparatus for annealing cold rolled strip steel. The invention includes numerous improvements upon, modifications of, and additions to annealing apparatus of the type shown in the prior patent of Cooper et al. No. 2,245,181, March 28, 1944, and in pending applications of Cooper et al., Serial Nos. 497,524, filed August 5, 1943, now Patent 2,521,044, and 565,014, filed November 24, 1944, now Patent 2,478,964 respectively. The primary object of the invention is to provide an apparatus which is capable of annealing strip steel having a high Rockwell number at an increased rate of production as compared with other continuous annealing machines, and to provide an apparatus which is capable of annealing strip steel having a lower Rockwell number than was possible with prior machines.

Another object of the invention is to provide a machine which is more flexible in operation, so that various annealing cycles may be followed, to produce different characteristics as to hardness and ductility in the annealed product. To this end, the invention provides an apparatus having an extended holding or soaking zone, which may be adjusted as to time duration and temperature, to produce the desired effects on the strip steel.

Another object is to provide an annealing apparatus in which the heating zone is adjustable as to temperature and time duration, making it possible to employ various different heating portions in different annealing cycles. A further object of the invention is to provide an apparatus in which a certain portion or portions thereof may be used selectively as heating or holding sections, to vary the annealing cycle.

Another object is to provide improved temperature controlling means in the holding and cooling zones of the apparatus, including improved gas circulating and cooling devices.

Another object is to provide an apparatus in which access to the interior may be had more readily than has heretofore been possible.

Another object of the invention is to improve the mounting of the strip guiding rolls, to the end that they may run substantially free in positively cool bearings sealed in gas-tight relation from the outside of the apparatus.

2

Other and further objects and advantages will be apparent from a consideration of the following description of a preferred embodiment of the invention, shown for purposes of illustration in the accompanying drawings, in which

Figure 1 is a side elevation of the annealing apparatus, with certain conventional strip handling mechanisms associated therewith;

Figure 2 is a diagrammatic plan view of Figure 1;

Figure 2a is an enlarged elevation of the cooling section, looking from the opposite direction as compared to Figure 1;

Figure 3 is a transverse section substantially on line 3—3 of Figure 1;

Figure 4 is a fragmentary, somewhat diagrammatic, longitudinal section through the heating and holding sections of the apparatus with certain parts omitted;

Figure 4a is a fragmentary section on an enlarged scale on line 4a—4a of Figure 4;

Figure 4b is a similar section on line 4b—4b of Figure 4;

Figure 4c is a similar section on line 4c—4c of Figure 4;

Figure 5 is an enlarged longitudinal section, with a central portion broken away, showing the interior of the first heating sections;

Figure 6 is a transverse section substantially on line 6—6 of Figure 5;

Figure 7 is a fragmentary, sectional perspective of one of the removable furnace bottoms;

Figure 8 is a section and partial elevation showing a preferred roll and roll supporting mechanism;

Figure 9 is an elevation taken from the right of Figure 8, and

Figure 10 is a section substantially on line 10—10 of Figure 8.

Referring to Figure 1, the annealing apparatus, represented generally at 5 includes a heating section 6, a holding or soaking section 7 and a cooling section 8. The annealer is positioned in the mill, above the floor 9, between infeed and outfeed strip handling devices of known type, including at the infeed end, a pair of coil unwinders 11 and 12, a welder 13 for attaching the trailing end of one strip to the leading end of another strip and a looper 14, providing an excess supply of strip which may be delivered continuously to the annealing apparatus during the time that the delivery of strip from the unwinder is arrested, while the tail end of one strip is being welded to the leading end of the next. At the delivery end, the strip handling devices include

3

a discharge looper 15 and a coiler 16 and a shear, not shown. Since these instrumentalities are described more in detail in the above identified patent and applications, and are well-known in the practical art, they need not be further described.

The annealing apparatus is supported above the mill floor 9, and preferably above a pit 20 therein, by a structural steel framework including a plurality of pairs of spaced uprights 21, 22, 23, 24, upper and lower longitudinally extending members 25, 26, and 27, and a plurality of transverse members 28, spaced apart at suitable distances. The heating and holding sections 6 and 7 of the apparatus, as hereinafter described, are enclosed within a sheet metal shell 29, which includes longitudinally extending front and back sections and appropriate end portions. Also, the shell includes longitudinally extending bottom walls 30 below the front and back walls and fixed transverse bottom sections 31, spaced apart longitudinally and between which removable bottoms are positioned as explained below.

The space within the shell is lined with relatively thick, heavy refractory brickwork providing longitudinally extending, vertically disposed, parallel front and back walls 32, 33, end walls 34 and 35 and a plurality of transverse walls. As shown in Figures 4 and 5, the transverse walls in the heating section, at the left, are arranged in two groups, with the individual walls of the groups alternating with each other, the first group including walls 36, 37 and 38, extending from the fixed bottom wall sections 39, upwardly, but terminating short of the upper edges of the longitudinal walls. The other group consisting of transverse walls 40, 41 and 42 extend upwardly to fixed top walled sections 43 and downwardly toward the bottom, but in spaced relation thereto, the lower ends of the walls being of arched form as indicated at 44 (Figure 4a) supported from the longitudinal walls.

The several walls just described define a plurality of vertically extending, heating chambers 45, 46, 47, 48, 49 and 50 through which the strip is trained successively in a serpentine path, upwardly through the first chamber, downwardly through the next, and so on. In the spaces above the first group of transverse walls 36-38, pairs of strip guide rolls 51 and 52 are mounted, to guide the strip from one chamber to the next. Similarly, below the other group of transverse walls 40-42, pairs of guide rolls 53 and 54 are mounted, under which the strip passes from one chamber to the next.

Below the first heating chamber 45 is a removable bottom wall section 55, having a relatively narrow slot 56 therein through which the strip enters the chamber. The removable bottom section includes a shell plate 31' of the type previously mentioned, supported by a rectangular, channel member frame 57, carried by longitudinally extending channels 58 having their ends bolted to the lower surfaces of channel brackets 59 carried by the transverse frame members 28. A gas-tight roll seal 60 of the type shown and described in the above mentioned patent and applications is suspended below the slot 56 to prevent the entrance of external air into the chamber. The strip is delivered to the gas-tight seal by an external guide roll 61, which receives the strip from the infeed looper 14.

The upper ends of the pairs of heating chambers on opposite sides of walls 36, 37, and 38 are closed by removable hoods or covers 65, 66, 67

4

of substantially identical construction as best shown in Figures 3 and 5. Each hood includes a metallic shell having a transversely arched top 68, vertical side and end walls 69 and 70, and an inturned bottom section 71, extending completely around the margin thereof. The interior of the shell is lined with refractory brickwork 72 of arched form and including vertically disposed end and side wall portions.

The shell end and side walls 69 and 70 are bounded by an outwardly facing channel 73, to which a depending flange 74 is secured, with its lower portion extending downwardly into a continuous channel 75, carried by the main furnace shell 29 and extending entirely around each hood. The several channels are filled with a suitable liquid, such as water, thereby providing, in cooperation with the flanges 74, a gas-tight liquid seal for the removal of the covers.

The lower ends of the pairs of heating chambers on opposite sides of the other group of transverse walls 40, 41 and 42 are closed by removable bottoms, a typical one of which is shown in Figures 5, 6 and 7. These bottoms include lower shell plates 31' upon each of which is mounted a relatively thick body of brickwork 80. The plates are mounted upon the upper webs of channel members 81 constituting a rectangular supporting frame, disposed, in turn, upon longitudinally extending channel members 82, having their ends bolted to the lower surfaces of channel brackets 83, projecting longitudinally from the transverse I-beams 28 and secured in place by vertical webs 84. Except for the matters of dimension, all of the removable bottom sections and their supporting structures, including the section 55, may be identical.

The rectangular supporting frame 81 has on its exterior surface a marginal trough 85 which may be filled with a sealing liquid, such as water, and into which a continuous flange 86 projects, the latter being carried by the fixed bottom wall sections 30 and 31 of the furnace shell, thereby providing a gas-tight liquid seal, preventing the admission of atmospheric air or the escape of the non-oxidizing gas between the removable bottom sections and the adjacent fixed furnace walls.

Access to the interior of the heating sections may be had by lifting the upper covers; for instance, by an overhead crane 88 (Figures 1 and 3) and by dropping the lower, removable bottom sections, by the use of suitable jacks, not shown, after the securing bolts have been released.

The end walls of the heating section and the transverse walls therein carry a plurality of refractory hangers 90 and guides or spacers 91 for radiant electric heating strips 92, which may be arranged as shown diagrammatically in Figure 6 so as to produce an even distribution of heat through the width of the strip steel and to prevent overheating of the edges thereof.

The control circuits for the several heating elements are so arranged that the ones in the last heating chamber 50 may be de-energized at will, leaving only the first five heating chambers in operation, and converting the sixth chamber 50 into a cooling chamber or first holding chamber in the holding zone, to prolong the holding portion of the annealing cycle. Since any appropriate control circuit may be employed, to render the elements in the final heating chamber selectively operable or inoperable, a circuit diagram is thought to be unnecessary.

As is well understood in this art, the entire interior of the annealing apparatus is filled with a

non-oxidizing gas, to prevent oxidation of the strip at the high temperatures to which it is raised. In accordance with the present invention, the heating, holding and cooling sections of the apparatus are independently supplied with a non-oxidizing gas such as a mixture of carbon dioxide and carbon monoxide and in some cases nitrogen. Preferably, the gas is delivered to the heating zone at the lower end of the final heating chamber 53, as indicated at 95 in Figure 4 thereby exerting a cooling effect on the strip, when that chamber is used as a cooling or holding chamber, with the heating elements de-energized. The gas flows slowly through the chambers 50-45 in a direction opposite to the movement of the strip and leaks outwardly through the roll seal 64, at the bottom of the entrance chamber 45.

The various strip guiding rolls may all be of substantially the construction shown in Figures 8-10 and may all be mounted in substantially the same way. The furnace shell 29 and the adjacent refractory wall 32 are provided with circular openings rimmed by an annular channel fitting 96, welded to the outer surface of the shell. A closure casting 97 includes a cylindrical body 98 extending into the above mentioned openings and an apertured plate 99 having its margins bolted to the channel fitting 96. The central aperture 100 in plate 99 communicates with a bearing receptacle 101, defined by an axially projecting, cylindrical wall 102. Surrounding the bearing receptacle is an annular chamber 103 for a cooling fluid, formed by an outer circumferential wall section 104 and an end wall 105.

The bearing receptacle 101 is closed by a cap 106 bolted to the end wall 105, with a suitable gasket interposed. Cooling liquid may be delivered to the chamber 103 by a pipe 107 leading from any suitable source of supply, through the circumferential wall 104, and the liquid may be discharged from the chamber through a pipe 108 extending through the marginal flange of cap 106 and the end wall 105. The burner 104 causes the water to circulate around the bearing in the direction of the arrows.

The roll 53 preferably has tapering ends, one of which is shown at 108, terminating in a journal 110, extending through the opening 100 in plate 99 and received in a roller bearing assembly 111 mounted in the bearing receptacle 101. The bearing may be supplied with lubricant by a pipe 112 extending from a nipple 113 through the outer circumferential wall 104, the inner wall 102 and the cage 114 of the bearing assembly. Preferably, the nipple 113 is enclosed by a cap 115, threaded upon a suitable collar 116 associated with the outer wall 104.

It should be understood that the supporting structure at the opposite ends of each roll may be identical to that shown in Figures 8-10. Each closure casting 97 may be filled with a suitable refractory insulating material 117, having a tapering inner surface, spaced fairly closely to the tapering end 109 of the roll to minimize heat losses. The several cooling chambers 103 may be supplied with cooling liquid from a common source by any suitable piping system, not shown, and the discharge pipes 108 may be similarly interconnected, for common disposal of the cooling liquid, or for re-circulation through a heat exchanger to the chambers.

The holding zone of the apparatus in accordance with the present invention consists of a plu-

rality of groups of vertically disposed, parallel chambers through which the strip is successively trained for movement. In the present instance, there are four groups, each including five interconnected chambers or passes, the first and last of which are of greater transverse dimension in horizontal section longitudinally of the apparatus, than the intermediate three chambers. As shown in Figure 4, the first group of chambers 120 in the holding zone comprises a first relatively wide chamber 121, defined at one end by the transverse wall 42 and at the other by the first of a pair of walls 123 and 124, which extend from the bottom upwardly toward, but spaced from the top wall or the upper edges of the longitudinal walls. The three intermediate chambers 125, 126 and 127, of less horizontal longitudinal dimension are defined by the said walls 123 and 124 and by another pair of walls 128 and 129 which extend from the top of the apparatus downwardly toward, but terminating in spaced relation to, the bottom thereof. The final chamber 130 of the first group 120 is of the same size as the first chamber 121 and is defined by the wall 129 and a relatively thick wall 131, separating the first group of chambers from the next group.

Above walls 123 and 124 and below walls 128 and 129 are single guide rolls 132 and 133, about which the strip is trained for passage through the chambers. Pairs of rolls are employed for transferring the strip around the ends of the relatively thick walls 42 and 131, etc., constituting the division walls between the successive groups of the chambers in the holding zone.

The upper ends of the several groups of chambers in the holding zone are closed by removable covers 135, 136, 137, and 138, while the bottoms are closed by removable bottom closure members 139, 140, 141, and 142, the construction of which may be similar to the corresponding elements previously described except that the covers 135, etc., need not be of arch form, but may be substantially flat as shown in Figures 4 and 4c, and comprised of a metal shell 143 and a refractory lining 144. The liquid seal arrangements may be substantially as previously described.

The several chambers in the holding zone are all filled with an atmosphere of a non-oxidizing gas of the type previously referred to. This gas is continuously circulated through the several chambers successively in a direction opposite to that of the movement of the strip through the chambers. Moreover, the gas after traveling through the chambers is withdrawn by suitable gas circulating means, through an external conduit, and returned to the last chamber of the holding zone for re-circulation therethrough. The heat picked up from the strip by the circulating gas is withdrawn therefrom during this return passage by one or more suitable heat exchangers.

Referring to Figures 1, 2, and 4, a blower 150 delivers the non-oxidizing gas through a discharge conduit 151 into the last chamber 130 of the last group of chambers in the holding zone, through an opening 152 in the front wall thereof. The gas, after flowing through the chambers successively and absorbing heat from the strip is withdrawn through an opening 153 in the front wall of chamber 121, at which point it passes through a heat exchanger 154, which may be of the well-known water cooled type. From the heat exchanger, the cooled gas flows through conduit 155 to the intake of the blower 150, from which point the cycle is repeated. Interposed in

the conduit 155, ahead of the fan 150, is a gate valve or damper 156, which is manually adjustable, to control the volume of flow of the gas and, hence, the amount of heat extracted from the strip steel, so that the holding portion of the annealing cycle may be varied at will and accurately controlled.

Although in the embodiment shown in the accompanying drawings, the gas circulating devices are positioned adjacent the top of the holding zone chambers, it should be understood that they may be positioned near the bottom thereof, or elsewhere, as desired.

Referring to Figure 1, it will be noted that an upper, supplemental framework 158 extends longitudinally toward the right and is supported by the uprights 23 and 24 and by another pair 159 constituting a part of the discharge looper 15. The framework 158 supports a generally rectangular, horizontally elongated casing 160, while a similar lower casing 161 is appropriately supported therebelow, in fixed position by the uprights 23 and 24. The casings are provided with a plurality of pairs of aligned openings in their front and back walls, in which closure members 97 are positioned, as previously described, to support strip guiding rolls in the casings. The upper casing 160 has a plurality of spaced openings in its bottom wall, to the margins of which a plurality of downwardly extending metallic chute sections 162 are secured. These sections are suspended from the upper casing 160, with their lower ends terminating in spaced relation above the lower casing, in alignment with openings in the top wall of the latter. The lower ends of the chute sections are connected to the lower casing 161 by flexible sections 162, which preferably take the form of Sylphon bellows of thin, flexible, sheet metal, sealed in gas-tight relation, respectively, to the chute sections and the casing and establishing communication therebetween. Thus, the cooling chutes, suspended from above, are free to expand and contract under the influence of temperature changes, the movement being permitted by the contraction and expansion of the bellows sections.

The lower casing 161 has its entrance end in communication with the discharge opening 163 (Figure 4) of the last holding zone section 130. The strip is trained about the first roll in the casing 161 and passes upwardly through the first cooling chute 162 to the first roll in the casing 160 over which it is trained for movement downwardly through the next cooling chute. It should be noted that the second, third, fourth, fifth, and sixth cooling chutes are relatively wide, longitudinally of the apparatus, while the first and seventh are relatively narrow. At the bottom of the second chute, the strip is trained about the second roll in casing 161 for movement upwardly through the same or second chute. At the upper end of the latter, the upwardly traveling strip passes over the second roll in casing 160, for downward movement in the third chute and so on. In other words, the rolls in the lower casing 160 guide the strip back upwardly through the same cooling chamber in which it descended, while the rolls in the upper casing 160 transfer the strip from one cooling chute to the next.

After passing downwardly through the last cooling chute, the strip is delivered, through any appropriate gas-tight seal mechanism for movement upwardly over an upper guide roll 165, from which point it travels downwardly under a guide roll 166, to the infeed rolls 167 of the de-

livery looper 15. As shown somewhat diagrammatically in Figure 1, the seal at the delivery end of the cooling section may comprise a water filled quench tank 170, into the open upper end of which a casing extension or delivery chute 171 projects, below the surface of the water. The strip passes below a guide roll 172 in the tank and then through a pair of wringer rolls 173 which remove excess surface water prior to its engagement with roll 165.

The interiors of the cooling chambers and of the upper and lower casings are filled with a non-oxidizing gas as previously described. This gas is circulated quite rapidly through the cooling chambers in a direction opposite to the direction of movement of the strip, preferably along two independent paths for two groups of sections, to facilitate the extraction of heat from the strip, by the use of two heat exchangers of high capacity. A first blower 175 delivers gas to the last cooling chute through a conduit 176, and this gas is withdrawn from the fourth cooling chute, at a point spaced from the upper end thereof, by a conduit 177, delivering to a heat exchanger 178, which, in turn, delivers the cooled gas to the intake of the blower 175. A second blower 179 delivers a stream of gas on another path through a conduit 180 to the upper end of the fourth cooling chute, at a point just above the conduit 177 which withdraws heated gas for delivery to the first heat exchanger. The gas passes from conduit 180 through the cooling chutes to the upper end of the first chute, from which point it is withdrawn by a conduit 181 for delivery to a second heat exchanger 182, the latter being in communication with the intake of blower 179. Hence, the strip is cooled by contact successively with two independent streams of positively cooled gas, flowing counter to the direction of movement of the strip. In this manner, the strip, although moving at a high rate of speed, may be quickly cooled below the oxidizing temperature for delivery through the quench tank to external atmosphere. Gate valves or dampers may be interposed in the gas circulating systems for the cooling section, or variable control may be effected by changing the speed of the blowers. However, since it is usually desired to cool the strip quite rapidly, after it leaves the holding zone, such adjustments are not often required.

It is through that the operation of the apparatus in accordance with the present invention will be understood from the foregoing description. All of the various chambers in the heating, holding and cooling zones are filled with a non-oxidizing gas, delivered through the opening or openings 95, adjacent the lower end of the sixth heating chamber, 50. The heating elements 92 are energized and the strip moving rapidly through the apparatus is quickly heated, primarily by radiation from the elements and from the adjacent refractory walls. The strip is raised to a temperature of 1800° F. or above in the heating zone. If it is desired to produce relatively high Rockwell steel, all six heating chambers are used to heat the steel and the speed of travel of the strip is raised, to increase the production rate. However, if lower Rockwell steel strip is to be produced, the speed is reduced and the sixth chamber is used for dropping the temperature from 1800° F. to substantially 1300° F., by de-energizing the heating elements in that chamber. The delivery of the non-oxidizing gas to the lower end of this sixth chamber assists in re-

ducing the temperature of the strip when so desired.

The temperature of the strip in the holding zone is accurately controlled and reduced gradually, in accordance with the particular annealing cycle being followed. The refractory, insulated walls between the successive passes in this zone prevents too rapid a drop in the temperature. The counter-current circulation of gas in the successive passes, with the control of the gas temperature and volume of flow, effected by the heat exchanger 154 and the valve 156 makes it possible to accurately control the holding portion of the annealing cycle. As a result of the construction described, it is possible to effect a relatively slow drop in temperature in the initial portion of the holding zone and a more rapid drop as the strip approaches the discharge end thereof.

In the cooling zone, the strip is still more quickly reduced in temperature, to a point where it will not be oxidized on exposure to external atmosphere.

The invention is not limited to the details of construction shown in the accompanying drawings and described above, but covers all modifications coming within the appended claims and their equivalents.

I claim:

1. An apparatus for annealing strip steel comprising a plurality of elongated, parallel chambers in endwise communication with each other, means for substantially sealing the chambers from external atmosphere, means for guiding continuous strip through the chambers successively, means in a first group of chambers, constituting a heating zone, for heating the strip to annealing temperature, means for introducing a non-oxidizing gas into the last chamber of said group adjacent the exit end thereof, means for selectively controlling the heating means in the last mentioned chamber, whereby it may be selectively converted from a heating chamber to a holding chamber to shorten the heating portion of the annealing cycle by rendering said heating means inoperative therein, means independent of the aforesaid gas introducing means for circulating a non-oxidizing gas through a second group of chambers, constituting a holding zone, in a direction opposite to that of the strip movement, and means independent of the aforementioned gas introducing means and gas circulating means for circulating an independent stream of non-oxidizing gas through a third and final group of chambers, constituting a cooling zone, in a direction opposite to that of the strip movement.

2. An apparatus in accordance with claim 1 in which the first-mentioned gas circulating means includes an inlet in the last chamber of the group constituting the holding zone, an outlet in the first chamber of said group, an external conduit connecting the inlet and the outlet, gas circulating means in said conduit and a variable heat exchanger in the conduit for extracting variable amounts of heat from the gas circulated therethrough.

3. An apparatus in accordance with claim 1 in which the means for circulating the gas through the third group of chambers includes an external conduit connected to the interior of spaced apart chambers, gas circulating means in said conduit and a heat exchanger for extracting heat from the gas in the conduit.

4. An apparatus for annealing strip steel comprising a heating section having front and back longitudinal walls and a plurality of parallel transverse walls dividing the space therein into a plurality of vertically disposed parallel, elongated chambers, alternate transverse walls extending upwardly from the bottoms of the chambers terminating short of the tops of the longitudinal walls, a pair of guide rolls above the upper ends of said alternate transverse walls for guiding strip steel thereover, the other alternate transverse walls extending downwardly from the tops of the chambers and terminating short of the bottoms of the longitudinal walls, and a second pair of guide rolls below the lower ends of said other alternate transverse walls for guiding the strip therebelow.

5. An apparatus for annealing strip steel comprising a heating section having front and back longitudinal walls and a plurality of parallel transverse walls dividing the space therein into a plurality of vertically disposed parallel, elongated chambers, alternate transverse walls terminating short of the tops of the longitudinal walls, a pair of guide rolls above the upper ends of said alternate transverse walls for guiding strip steel thereover, the other alternate transverse walls terminating short of the bottoms of the longitudinal walls, and a second pair of guide rolls below the lower ends of said other alternate transverse walls for guiding the strip therebelow, removable covers above the first mentioned pairs of rolls and removable, horizontally extending, bottom closures below the second mentioned pairs of rolls, substantially coextensive in area with the chambers thereabove.

6. An apparatus for annealing strip steel comprising substantially continuous longitudinally extending front and back walls, means at the upper and lower ends thereof providing top and bottom walls a plurality of vertically disposed transverse walls dividing the space between the longitudinal walls into a plurality of elongated parallel heating chambers, the first transverse wall being imperforate from the top of the bottom wall and constituting an end wall, the second transverse wall and the succeeding alternate walls extending upwardly from contact with the bottom wall and terminating at their upper ends below the top wall, the third and other alternate transverse wall extending downwardly from contact with the top wall and terminating at their lower ends above the bottom wall, and roll means above and below the two sets of alternate transverse walls for guiding strip steel in a serpentine path successively through the chambers.

7. Apparatus for annealing strip steel, comprising vertically disposed, parallel, horizontally and vertically elongated, substantially continuous longitudinal front and back walls, end walls closing the end spaces therebetween, a plurality of removable covers supported by the longitudinal walls constituting a sectional top wall, a bottom wall comprising a plurality of fixed sections and a plurality of removable sections alternating therewith, and a plurality of vertically extending, parallel transverse walls dividing the interior of the apparatus into a plurality of vertically elongated parallel chambers, said transverse walls consisting of a first alternate series terminating at their upper ends in spaced relation below the covers and at their lower ends in contact with the fixed sections of the bottom wall, and a second alternate series having their

lower ends spaced above the removable sections of the bottom wall and their upper ends in contact with said removable covers, and roll means above and below the first and second series of transverse walls respectively for guiding the strip in a serpentine path successively through the chambers.

8. Apparatus for annealing strip steel, comprising vertically disposed, parallel, horizontally and vertically elongated, substantially continuous longitudinal front and back walls, end walls closing the end spaces therebetween, a plurality of removable covers supported by the longitudinal walls constituting a sectional top wall, a bottom wall comprising a plurality of fixed sections and a plurality of removable sections alternating therewith and of greater longitudinal dimension than the fixed sections, and a plurality of vertically extending, parallel transverse walls dividing the interior of the apparatus into a plurality of vertically elongated parallel chambers, said transverse walls consisting of a first alternate series terminating in spaced relation below the covers and a second alternate series having their lower ends spaced above the removable section of the bottom wall, and roll means above and below the first and second series of transverse walls respectively for guiding the strip in a serpentine path successively through the chambers, each chamber of a first group of chambers being of relatively greater horizontal section and constituting a heating zone and each chamber of a second group of chambers being of lesser horizontal section and constituting a holding zone.

9. An apparatus in accordance with claim 8, characterized in that, in said heating zone pairs of rollers are disposed above and below the successive transverse walls to guide the strip from one chamber to the next.

10. Apparatus in accordance with claim 8, characterized in that single guide rolls are journaled above and below a plurality of successive transverse walls in the holding zone to guide the strip successively through the chambers thereof.

11. An apparatus in accordance with claim 8, characterized in that the holding zone is divided into a plurality of groups of chambers, each group comprising three chambers of small horizontal section and entering and exit chambers of greater section and in that single rolls guide the strip into and out of the chambers.

12. An apparatus in accordance with claim 8, characterized in that the chambers in the holding zone are arranged in a plurality of groups and in that an independent removable cover closes the chambers of each group.

13. An apparatus in accordance with claim 12, characterized in that an independent removable bottom wall section closes the lower ends of the chambers of each group in the holding zone.

14. An apparatus for annealing strip steel, comprising vertically disposed parallel horizontally and vertically elongated front and back longitudinal walls, a plurality of transverse walls dividing the space therebetween into a plurality of vertically elongated parallel heating chambers, a plurality of removable covers supported by the longitudinal walls and by alternate transverse walls, each substantially coextensive in area with and closing the upper ends of a pair of chambers therebelow, a plurality of removable bottom closure members, each substantially coextensive in area with and closing a pair of chambers thereabove, roll means below the covers for

guiding the strip from one chamber to the next, and roll means above the removable bottom closures for guiding the strip from one chamber to the next.

15. An apparatus for annealing strip steel comprising substantially continuous longitudinally extending front and back walls, a bottom wall including alternate, fixed and removable sections, a top wall and a plurality of vertically disposed transverse walls dividing the interior space into a plurality of elongated parallel chambers, said transverse walls being arranged in two groups alternating with each other, a first group comprising individual walls each terminating at its lower end in an arch structure, spaced above the removable bottom wall sections and supported from the longitudinal walls, the other group comprising individual walls each extending upwardly from the fixed bottom wall sections and terminating in spaced relation below the top wall.

16. Means for supporting a strip guiding roll in a continuous annealing apparatus having a side wall provided with an opening through which the roll may pass, and an annular supporting fitting surrounding said opening and secured to the exterior surface of said wall, said means comprising a closure for the opening having a cylindrical body projecting through the furnace side wall along the margins of the opening, an apertured face plate at the outer end of said body, operatively secured to and supported by said fitting, means carried by the plate defining a bearing socket communicating with the aperture in the plate, means defining an annular cooling chamber surrounding the socket, a bearing in the socket for the roll journal, a cap for closing the outer end of the socket, and means for circulating cooling fluid through said chamber.

17. An appealing apparatus for strip steel comprising a supporting framework including a plurality of uprights and longitudinally and transversely extending lower members supported thereby, brickwork carried by said members defining a plurality of parallel vertically extending chambers through which the strip is trained for movement, and a plurality of removable bottom sections, each comprising longitudinal and transverse framing elements, refractory material supported thereby and means removably connecting said elements to certain of said lower members, whereby said sections may be lowered for access to said chambers.

18. An annealing apparatus comprising a supporting framework including a plurality of uprights and a plurality of longitudinally and transversely extending lower members supported thereby at points spaced well above the lower ends thereof, refractory walls carried by said members defining a plurality of parallel vertical chambers through which the strip is successively trained for movement, and a plurality of removable bottom sections closing the lower ends of the chambers, certain of said sections being of a size to close at least two adjacent chambers and comprising transversely projecting framing elements removably connected to certain of said lower members, whereby said sections may be lowered to give access to the chambers thereabove.

19. An annealing apparatus for strip steel comprising a supporting framework including a plurality of uprights and longitudinally and transversely extending lower members supported

75

thereby in spaced relation above the lower ends thereof, refractory walls carried by said members defining a plurality of parallel vertically extending chambers through which the strip is trained for movement, a plurality of removable bottom sections and means for supporting the same from the transverse members, said means comprising brackets projecting longitudinally from the transverse members, longitudinally extending channels below the sections and releasable means for securing said channels to the undersurfaces of the brackets, whereby the bottoms and the channels may be lowered to give access to the chambers.

20. An annealing apparatus for strip steel comprising fixed refractory wall members defining a plurality of parallel vertically extending chambers through which the strip is trained for movement, a plurality of fixed bottom members, a plurality of removable bottom sections, and means for sealing the space therebetween, said means comprising an upwardly opening channel carried by each removable section around the perimeter thereof, a continuous, fixed depending flange carried by certain of said members, projecting downwardly into and extending continuously around the channel, and a body of liquid in the channel in sealing contact with the flange.

21. An annealing apparatus for strip steel comprising a pair of fixed, elongated, parallel, vertical, longitudinally extending, refractory walls and a plurality of fixed, parallel, transverse refractory walls defining a plurality of parallel vertically extending chambers through which the strip is trained for movement, a plurality of fixed bottom walls and a plurality of removable bottom sections disposed between certain of the said walls, and means for sealing the space around the perimeter of each removable section, each of said means comprising an

upwardly opening channel suspended below the level of each section in substantial alignment with and below the perimeter thereof, a continuous depending flange carried by the adjacent fixed walls in gas-tight relation with respect thereto, projecting downwardly into and extending continuously around the channel, and a body of liquid in the channel in sealing contact with the flange.
